UNITED STATES PATENT OFFICE.

EMIL PIRON, OF NEW YORK, N. Y., ASSIGNOR TO PIRON COAL DISTILLATION SYSTEMS, INC., OF NEW YORK, N. Y., A CORPORATION OF DELAWARE.

PURIFYING GASES.

Application filed January 7, 1925. Serial No. 957.

In wood distillation the condensable products from the wood retorts are roughly classified into two products, viz, the non-aqueous, including the various light oils and tar collectively termed "tar", and an aqueous portion containing acetic acid, methyl alcohol, acetone and other substances including water itself, known as pyroligneous acid or "green liquor". Heretofore it has been customary practice to condense both pyroligneous acid and tar (including the light oils) together, allowing the aqueous and non-aqueous portion to separate and then to decant one layer from the other. It is not practicable, however, to fractionate the separated pyroligneous liquor directly, due to the fact that the separation of the tar is never complete and the tar present, clogs the condensing and fractionating apparatus. It is therefore necessary first to subject the entire pyroligneous acid to a preliminary distillation in order to eliminate tar as much as possible.

Due to the expense involved in this preliminary distillation step, numerous methods have been proposed for eliminating the tar from the distillation gases prior to the condensation of the pyroligneous acid. In all of these methods, some tar scrubbing medium is used, but so far as I am aware, none of these methods has been entirely successful due to the fact that a slight amount of tar or tar-forming material is left in the pyroligneous acid vapors which, however small, will gradually plug up the plates of the distilling columns and render cleaning necessary at frequent intervals. It is my belief that the presence of tar in the acid product is due to the presence of tar-forming substances which elude condensation or absorption by the scrubbing medium and that therefore, it is not practicable to remove all the tar by purely physical means alone.

In accordance with my present invention, I preferably subject the distillation gases (by which term it is, of course, meant to include what, strictly speaking, are vapors) to a preliminary washing operation, using a known scrubbing medium, whereby the major portion of the tar is removed from the gases, or, if my theory is correct, perhaps all of the tar then present in the gases as such. I then subject the gases, while maintaining them at a suitable temperature, to the action of one or more substances

which I have found will effectively remove all the remaining tar and tar-forming elements, whereby the pyroligneous liquor obtained will be substantially entirely free of tar. The substances which I have found to possess this tar-removing property are, first, those which exert a moderately strong oxidizing action under the conditions present (it should be kept in mind that the retort vapors are strongly acid), and, second, acids which are not volatile under the pressure and at the temperature prevailing in the scrubber. Among the first class of substances I may mention chlorine, potassium permanganate, potassium dichromate and hydrogen peroxide, while in the second class, sulphuric, phosphoric and oxalic acids have been found effective. I greatly prefer, however, sulphuric acid of suitable concentration as the sole scrubbing medium, since it is not only an acid which meets the above-named requirements as an acid, but it is also an oxidizing agent as well, so that by using sulphuric acid alone I obtain as good, if not better, results as those had by using a separate oxidizing agent and a separate acid. It will be understood that the tar may be removed by the oxidizing agent alone, but I have found that the action of such agent is not only facilitated by the presence of the acid, but the character of the tar separated renders it more easily removed from the scrubber. It now seems that the action of the two classes of substances is that the oxidizing agent initiates the conversion of the tar-forming substances into tar while the acid acts as a catalyst in such reaction.

As above stated, I preferably remove the greater part of the tar by a preliminary washing or scrubbing with a medium having no appreciable chemical effect upon the tar itself; however, if desired, all of the tar may be removed in one scrubbing step, as by scrubbing with sulphuric acid of the proper concentration alone or by scrubbing with other media in the presence of sulphuric acid or the other substances I have mentioned. In this case, however, the tar obtained will be contaminated with the special scrubbing material used and in general must be separated from it, as by neutralization, etc. For this reason, I prefer to remove the tar in two or more steps, as stated.

The accompanying drawing illustrates

diagrammatically one arrangement of apparatus suitable for carrying out my improved method. In this arrangement the distillation gases from the retort are first passed 5 through what I have denominated a "green liquor" scrubber, in which the gases are scrubbed and deprived of a large proportion of their tar using ordinary green liquor or crude pyroligneous acid as the scrubbing 10 medium. This liquor is recirculated through the scrubber which is maintained at a temperature above the boiling point of the pyroligneous acid. Of course, some of the green liquor is evaporated, but enough is 15 used so as to accomplish a thorough scrubbing.

From the green liquor scrubber the gases pass to what I have designated the sulphuric acid scrubber. Prior to their introduction 20 to this scrubber, I generally find it necessary to raise the temperature of the gases and do so preferably by mixing therewith a sufficient quantity of heated uncondensable gases from the condenser and thereby prevent the 25 temperature of the gases being lowered to a point below the condensation of the pyroligneous liquor constituents. In practice, I have found it satisfactory to maintain the temperature within the sulphuric acid scrub- 30 ber slightly above 100° C. so that the concentration of the sulphuric acid solution remains at about 30 Be'. It will be noted that the temperature of the scrubber determines the strength of the acid, since, if a strength 35 of acid is used which has a higher boiling point than the scrubber temperature, water will be absorbed from the vapors until an acid of this boiling point is reached, whereas if the acid has a boiling point lower than 40 the scrubber temperature, water will evaporate until the boiling point of the acid mixture corresponds to that of the scrubber temperature.

After the acid has recirculated sufficiently, 45 it is drawn off and separated from the tar by decantation, whereupon the acid may be used over again. If desired, this separation step may, of course, be made continuous. Some of the acid combines with impurities 50 of a basic nature, but the amount of such impurities is relatively small.

From the sulphuric acid scrubber, the 55 gases pass to a condenser where the pyroligneous acid is condensed. As shown, the residual gases are conducted from the condenser by means of a suitable exhauster and are led back to be burned beneath the retorts or for other disposition. A portion of them is passed through a re heater and then intro-

duced into the sulphuric scrubber, as above 60 described. The pyroligneous acid obtained is substantially entirely free from tar and tar-forming elements and may be fed directly to the fractionating columns and the acetic acid and methyl alcohol recovered 65 immediately without neutralization of the acetic acid.

It will be seen that, by thus completely eliminating tar from the pyroligneous acid, many advantages and economies result. 70 For example, my improved method is applicable to sawdust containing large amounts of water, wet sawdust being very difficult to dry. The pyroligneous acid obtained from such a material is naturally very dilute, 75 rendering prohibitive the cost of a preliminary distillation thereof for the purpose of removing the tar. In my method, however, this step is obviated. A further advantage of the improved method is that it permits 80 the direct fractionation of the pyroligneous acid into acetic acid and methyl alcohol without previously neutralizing the acetic acid. Moreover it gives a liquor from which an acetate of lime of higher concentration 85 can be obtained.

I claim:

1. In the art of wood distillation, the method of removing tar and tar-forming elements from distillation gases which consists in washing said gases with a solution of sulphuric acid while maintaining the temperature of the gases above the condensing point of the nontar vapors.

2. In the art of wood distillation, the method of removing tar and tar-forming elements from distillation gases which consists in washing said gases with a scrubbing medium having substantially no chemical action upon the tar constituents to remove 100 the greater portion thereof, then scrubbing said gases with a sulphuric acid solution while maintaining the temperature of the gases during said scrubbing steps above the condensing point of the nontar vapors.

3. In the art of wood distillation, the method of removing tar and tar-forming elements from distillation gases which consists in washing said gases with a scrubbing medium having substantially no chemical 110 action upon the tar constituents to remove the greater portion thereof, heating said gases then scrubbing said gases with a sulphuric acid solution while maintaining the temperature of the gases during said scrubbing steps above the condensing point of the nontar vapors.

EMIL PIRON.
